UNITED STATES PATENT OFFICE

ALEXANDER C. PARLINI, OF WOODSIDE, NEW YORK, ASSIGNOR TO GOTHAM KNITBAC
MACHINE CORPORATION, A CORPORATION OF DELAWARE

RE-KNITTING APPARATUS

Application filed July 9, 1929. Serial No. 377,016.

This invention relates in general to re-knitting apparatus and more particularly to manually operated apparatus for repairing runs, ravelled, dropped stitches and the like, in 5 stockings, underwear and other knitted fabrics. When runs and the like are re-knitted in fabrics considerable skill is required on the part of the operator in positioning the repairing needle and in reciprocating the same 10 with respect to the threads of the run.

With each type of repairing needle, the needle is preferably held in a particular angular relation with respect to the run. With certain types of repairing needles, it is necessary to position them laterally out of alignment with the run during the repairing operation. As this positioning of the repairing needle must be maintained constant during the repairing operation, the operator's hand 20 becomes quickly fatigued and the efficiency of the operator greatly decreased accordingly. Therefore, the principal object of the present invention is to provide an accurate manually operated re-knitting apparatus 25 which is supported upon the fabric at a fixed angle with respect to the run thereby rendering it unnecessary for the operator to support the apparatus by hand and to maintain same in a fixed position during the repairing 30 operation.

In re-knitting a run, in order to avoid the dropping of stitches and to re-knit efficiently, it is necessary for the operator to employ a re-knitting stroke of a particular length. If 35 the stroke employed is too short, the needle is apt to be raised before the next thread of the run has been caught in the hook of the needle and the stitch on the needle shank will be dropped when the needle is raised. Any 40 lowering of the needle beyond the place where the threads pass over the end of the latch in its open position is unnecessary and inefficient. Therefore, it becomes desirable to provide means for controlling the length of the 45 re-knitting stroke within certain well defined

limits. Another object of the invention, therefore, is to provide a manually operated apparatus having associated therewith adjustable means for controlling the length of the stroke of the re-knitting needle. 50

When a run in the fabric is re-knitted, the threads of the run are successively formed into loops and the successive loops are interengaged by the reciprocation of the repairing needle. It will, therefore, be understood that 55 in order to repair a run either the fabric must be fed to the repairing needle or the repairing needle advanced longitudinally along the run. Another object of the present invention is to provide means whereby the 60 reciprocation of the repairing needle causes the re-knitting apparatus to be advanced longitudinally along the run in the fabric. As hereinafter described, the repairing apparatus is advanced along the run during the 65 upward movement of the repairing needle so as to insure the catching of the threads of the run in the hook of the needle when the needle is raised.

A further object of the present invention is 70 to provide a manually operated re-knitting apparatus of such construction that the repairing needle is reciprocated by the reciprocation of a handle member operated by the hand of the operator in a simple and rapid 75 manner.

Further objects of the invention will be apparent from the following description and the invention will be better understood when the description is taken in conjunction with 80 the accompanying drawing in which,

Fig. 1 is a cross sectional side view of a preferred form of apparatus embodying the present invention,

Fig. 2 is a front view thereof, 85
Fig. 3 is a cross sectional side elevational view similar to Fig. 1 but illustrating in addition thereto a presser foot mechanism for advancing the apparatus longitudinally 90 along the run in the fabric,

Fig. 4 is a partial enlarged side elevational view of the above mentioned presser foot mechanism,

- Fig. 5 is a top view of the presser foot, and
- Fig. 6 is a perspective view of the presser foot construction.

In the drawings the numeral 1 indicates a latch needle of the usual design such as is commonly used in repairing or re-knitting 10 runs, ravelled stitches and the like, in stockings, underwear and other knitted fabrics. The needle 1 is held in a suitable needle holder 2 preferably cylindrical and of substantial length as illustrated in the 15 drawings. The needle holder is supported in a sleeve 3 and is reciprocable therein by movement of a handle member to be described hereinafter. As shown in the drawings, the needle holder 2 projects slightly beyond the up- 20 per end of the sleeve 3.

The lower end of the sleeve 3 is preferably provided with a collar 4 securely fastened to the sleeve 3 in any suitable manner. A presser foot 5 adapted to support the re-knitting apparatus in a fixed relation to the run in the fabric is connected to the lower end of the collar 4.

A handle 6 preferably cylindrical surrounds the sleeve 3, and is connected to the 30 needle holder 2 by means of a pin 7 which passes through a longitudinal slot 8 in the sleeve 3 and engages in the needle holder 2 as shown more clearly in Fig. 1. The slot 8 in the sleeve 3 is preferably of such length 35 that the pin 7 limits the downward movement of the needle holder 2 relative to the tube 3 and presser foot 5. It will be appreciated, of course, that since the sleeve 3 and collar 4 mounted thereon are rigidly connected 40 to the presser foot 5, they are stationary during the operation of the apparatus, while the handle 6 and the needle holder 2 carrying the needle 1 are reciprocable by the hand of the operator.

45 The lower end of the handle 6 is recessed as indicated at 9 and a helical spring 10 lies in this recess and abuts against the collar 4 and the upper end of the recess as shown more clearly in Fig. 1. This spring serves 50 to return the handle 6 to its upper position after it has been depressed by the hand of the operator.

In re-knitting runs in stockings and other knitting fabrics by hand, it is desirable that 55 the length of the stroke of the re-knitting needle be made uniform so as to avoid the risk of dropping stitches due to lifting the needle too short a distance or depressing it too little. It requires considerable skill on 60 the part of the operator to maintain the required length of stroke for any considerable time and is a source of inconvenience to the operator. The apparatus described herein is designed to provide adjustable means for 65 controlling the length of the stroke of the

re-knitting needle. As previously mentioned, the upward movement of the sleeve 3 is limited by the pin 7 striking against the upper edge of the slot 8 in the sleeve 3. The opposite movement of the repairing needle is limited by means of an adjustable nut 11 screwed on the threaded upper end of the needle holder 2, as shown in the drawings. When the needle holder 2 is depressed by the handle 6, the nut 11 will strike against the upper end of the stationary sleeve 3 and thus restrict the downward movement of the repairing needle. It will, of course, be appreciated that the length of the slot 8 in the sleeve 3 and the position of the adjustable nut 11 on the needle holder 2 may be varied so as to change the length of the stroke of the repairing needle as desired.

As shown in Figs. 1 and 2, the apparatus herein described is adapted to be operated in the vertical plane of the run in the fabric. It will be understood with other types of re-knitting needles, it is often desirable and sometimes essential that they be used in a position laterally out of alignment with the run in the fabric. If such arrangement be desirable, the presser foot may be changed so as to position the apparatus at the desired angle.

Referring now more particularly to Figs. 3-6 inclusive, the presser foot mechanism which is adapted to advance the repairing apparatus longitudinally along the run in the fabric will now be described. The presser foot 5 is preferably provided with two spaced ears 12 which are adapted to support a rotatable pin 13 extending beyond the sides of the presser foot as more clearly illustrated in Fig. 5. The sides of the presser foot are recessed as indicated at 14 in Fig. 5 so as to accommodate two presser rollers 15 mounted upon the rotatable pin 13 and of such diameter that they project slightly below the lower surface of the presser foot 5, as shown more clearly in Figs. 3 and 4. The rollers 15 are provided on their outer faces with ratchet wheels 16 with which the pawls 17 engage to rotate the rollers. The pawls 17 are pivoted upon the lower end of a yoke 18 and are normally urged toward the ratchet wheels 16 by the springs 19. The yoke 18, as shown in Fig. 5, is provided with two spaced branches 20 which lie in close proximity to the face of the ratchet wheels 16 and which have an elongated slot 21 through which the ends of the rotatable pin 13 pass.

The upper end of the yoke 18 is connected to the lower end of the handle 6 by a collar 22 clamped thereon or by any other suitable means. The sides of the slots 21 in the lower branches 20 of the yoke are parallel with the center line of the needle holder 2.

It will be understood from the above description that when the handle 6 is reciprocated by the hand of the operator and by the

helical spring 10, the repairing needle 1 will likewise be reciprocated and in the usual manner will successively form loops in the threads of the run and will progressively interengage the successive loops thus formed to re-knit the fabric. To one skilled in the art, it will be apparent that during this re-knitting operation the repairing apparatus must be moved longitudinally along the run or the fabric advanced to the repairing apparatus. In the operation of the present apparatus, the fabric is held stationary and the apparatus advanced longitudinally along the run to be re-knitted. As the handle 6 of the apparatus is reciprocated as above described, the yoke 18 connected thereto reciprocates and carries with it the pawls 17 which being in engagement with the teeth of the ratchet wheels 16, cause the latter to rotate the presser rollers 15. These rollers travel along the fabric and move the entire apparatus longitudinally along the run so as to permit the repairing of the run without requiring the operator to move the apparatus other than to reciprocate the handle 6.

Having thus described this specific embodiment of my invention, it is not to be understood that the invention is limited to the details of form and the arrangement of parts set forth for various changes may be made by those skilled in the art without departing from the spirit and scope of the invention as set forth in the appended claims.

What I claim and desire to protect by Letters Patent is:

1. A fabric re-knitting apparatus comprising, a sleeve having a longitudinal slot therein, means for determining the position of said sleeve relative to said fabric, a needle holder reciprocable in said sleeve, a handle surrounding said sleeve, means extending through said slot and connected to said handle and said holder whereby said handle is adapted to reciprocate said holder and means for limiting the length of the stroke of said holder.

2. A fabric re-knitting apparatus comprising, a sleeve having a longitudinal slot therein, means for determining the position of said sleeve relative to said fabric, a needle holder reciprocable in said sleeve and having one end projecting beyond said sleeve, a handle surrounding said sleeve, means extending through said slot and connected to said handle and said holder whereby said handle is adapted to reciprocate said holder and means associated with the projecting end of said holder for limiting the length of the stroke of said holder.

3. A fabric re-knitting apparatus comprising, a sleeve, means for determining the position of said sleeve relative to said fabric, a needle holder reciprocable in said sleeve, an abutment on the end of said sleeve, a handle adapted to reciprocate said holder, resilient

means between said abutment and said handle and means for adjusting the length of the stroke of said holder.

4. A fabric re-knitting apparatus comprising, a sleeve, means for determining the position of said sleeve relative to said fabric, a needle holder reciprocable in said sleeve and having one end projecting beyond said sleeve, an abutment on the end of said sleeve, a handle adapted to reciprocate said holder, resilient means between said abutment and said handle and means associated with the projecting end of said holder for adjusting the length of the stroke of said holder.

5. A fabric re-knitting apparatus comprising, a sleeve having a longitudinal slot therein, a presser foot carried by said sleeve, a needle holder reciprocable in said sleeve, an abutment on the end of said sleeve, a handle surrounding said sleeve, means extending through said slot and connected to said handle and said holder whereby said handle is adapted to reciprocate said holder, resilient means between said abutment and said handle and means for controlling the length of the stroke of said holder.

6. A fabric re-knitting apparatus comprising, a sleeve having a longitudinal slot therein, a presser foot carried by said sleeve, a needle holder reciprocable in said sleeve and having one end projecting beyond said sleeve, an abutment on the end of said sleeve, a handle surrounding said sleeve and having a recess in one end thereof, means extending through said slot and connected to said handle and said holder whereby said handle is adapted to reciprocate said holder, resilient means between said abutment and said handle and lying in said recess and means associated with the projecting end of said holder for controlling the length of the stroke of said holder.

7. An apparatus for re-knitting runs in fabrics comprising, a sleeve, means for determining the position of said sleeve relative to said fabric, a needle holder reciprocable in said sleeve, a handle adapted to reciprocate said holder, means for controlling the length of the stroke of said holder and a feeding mechanism for advancing the apparatus longitudinally of the run comprising, rollers and means operated by the reciprocation of said handle and adapted to rotate said rollers.

8. An apparatus for re-knitting runs in fabrics comprising, a sleeve, a needle holder reciprocable in said sleeve, a handle adapted to reciprocate said holder, means for controlling the length of the stroke of said holder and a feeding mechanism for advancing the apparatus longitudinally of the run comprising, a presser foot, rollers supported thereby, and reciprocable means connected to said handle and said rollers and adapted to rotate said rollers.

9. An apparatus for re-knitting runs in

fabrics comprising, a sleeve, a needle holder reciprocable in said sleeve, a handle adapted to reciprocate said holder, means for controlling the length of the stroke of said holder and a feeding mechanism for advancing the apparatus longitudinally of the run comprising, a presser foot, rollers supported thereby, a ratchet associated with said rollers, a pawl coacting therewith and a member connected to said handle and said pawl and reciprocable with said handle, said pawl being adapted to rotate said ratchet during the upward movement of said handle.

15 In testimony whereof I affix my signature.
ALEXANDER C. PARLINI.
